Attorney

UNITED STATES PATENT OFFICE.

JOHN G. SJOBERG, OF OAKLAND, CALIFORNIA.

SHIP-LAUNCHING CONTROL DEVICE.

1,339,293.

Specification of Letters Patent. Patented May 4, 1920.

Application filed June 30, 1919. Serial No. 307,586.

To all whom it may concern:

Be it known that I, JOHN G. SJOBERG, a citizen of the United States, residing at Oakland, in the county of Alameda and 5 State of California, have invented certain new and useful Improvements in Ship-Launching Control Devices, of which the following is a specification.

My invention is a ship launching control 10 device.

In this specification and the annexed drawing I disclose my invention in the form which I consider the best, but I do not limit my invention to such form because it 15 may be embodied in other forms and it is to be understood that in and by the claims following the description herein I intend to cover my invention in whatever form it may be embodied.

20 Referring to the drawing:

Figure 1 is a side view of my invention applied to a ship way.

Fig. 2 is an enlarged side view of my invention.

25 Fig. 3 is an end view of one of the shoes of the shore bar.

In the drawing 1 indicates a ship way including the stationary supporting frame 2 and the slide frame 3 slidable on frame 2, 30 on which slide frame are the cradles 4 in which rest a ship 5. To the frame 2 is secured an abutment bar 6 and to the frame 3 is secured an abutment bar 7, between the ends of which are interposed a shore bar 8 35 which holds the slide 3 on the frame 2.

Metal shoes 9 and 10 are fitted on the abutting ends of abutment bars 6 and 7 respectively and metal shoes 11 and 12 are fitted on the ends of shore bar 8 which respectively 40 engage the shoes 9 and 10. The shoe 11 is formed with a vertical slot 13 in its lower side and two lugs 14 depending therefrom at the sides of said slot in which lugs a locking lever 15 is pivoted by the pivot 16, 45 on which lever is a latch 17 adapted to extend through slot 13 into a notch 18 in the abutting side of shoe 9 of abutment bar 6. A cam 19 is formed on the pivoted end of lever 15. A weight 20 is formed on the 50 swinging end of lever 15. To the weight 20 is secured an eye 21 adapted to be engaged by a trigger 22 pivoted in a bracket 23 depending from the under side of the shore bar 8, said bracket having a shank 24 extending through said bar on the outer end of which screws a nut 25 against the upper

part of said bar whereby the bracket is secured to the bar. The shoe 12 has a lug 26 projecting from the lower edge of its abutment end which depends at an angle under 60 the lower edge of the abutment end of shoes 10 for engaging the lower side of said shoe. A weight 27 is connected by a rope 28 to the frame 2 and by a rope 29 to the swinging arm of trigger 22.

65 Before the ship is launched the lever 15 is held as shown in the drawing by the engagement of trigger 22 with eye 21 with the latch 17 extended through slot 13 into notch 18, and the weight 27 is suspended from the 70 frame 2 by rope 28. The engagement of latch 17 with notch 18 prevents the shore bar from being forced downward in any way and disengaged from the abutment bar 6 so as to launch the ship.

75 To launch the ship the rope 28 is cut, whereupon the weight 27 drops and disengages the trigger 22 from eye 21; the lever 15, under the influence of weight 20 is swung down, disengaging the latch 17 from 80 notch 18 and causing the cam 19 to engage the bottom of shoe 9; and the weight 20, assisted by the cam 19 engaging shoe 9, withdraws the shore bar 11 downward out of engagement with abutment bars 6 and 7, lug 85 26 engaging the under surface of shoe 10 and preventing the upper end of the shore bar from flying up, thus releasing frame 3 and launching the ship.

Having described my invention, I claim: 90

1. In combination, abutments on the stationary and sliding frames respectively of a ship way, a shore bar interposed between said abutments, locking means for one end of said shore bar, and means for preventing 95 the other end of said bar from flying upward when the bar is disengaged at its locking end.

2. In combination, abutments on the stationary and sliding frames respectively of a ship way, a shore bar interposed between said abutments, a lever on said shore bar, a latch on said lever for engaging one of said abutments to hold the bar against said abutment, and means for swinging said lever to 105 disengage said latch from said abutment.

3. In combination, abutments on the stationary and sliding frames respectively of a ship way, a shore bar interposed between said abutments, a weighted lever pivoted on 110 said shore bar, a latch on said lever for engaging one of said abutments to lock said

bar against said abutment, and a trigger for holding said lever with said latch in engagement with said abutment.

4. In combination, abutments on the stationary and sliding frames respectively of a ship way, a shore bar interposed between said abutments, a weighted lever pivoted on said shore bar, a latch on said lever for engaging one of said abutments to lock said bar against said abutment, a trigger for holding said lever with said latch in engagement with said abutment, and a weight connected to said trigger but suspended from the ship way before launching the ship.

5. In combination, abutments on the stationary and sliding frames respectively of a ship way, a shore bar interposed between said abutments, locking means for one end of said shore bar, and a lug on the other end

of said bar for engaging the adjacent abutment to prevent said end of the bar from flying up when the bar is disengaged at its locking end.

6. In combination, abutments on the stationary and sliding frames respectively of a ship way, a shore bar interposed between said abutments, a weighted lever pivoted on said shore bar, a latch on said lever for engaging one of said abutments to hold the bar against said abutment, a cam on said lever for engaging said abutment to assist the weighted lever in disengaging the shore bar from said abutment when said lever is released, and means for holding up the lever with said latch in engagement with said abutment.

In testimony whereof I affix my signature.

JOHN G. SJOBERG.
